DESIGN FOR A COMBINED CALENDAR AND SCRATCH PAD HOLDER

James H. Horsley, Chicago, Ill., assignor to
Shanklin Manufacturing Company, Chicago,
Ill., a corporation of Illinois

Application July 24, 1939, Serial No. 86,201

Term of patent 14 years

To all whom it may concern:

Be it known that I, James H. Horsley, a citizen of the United States and resident of Chicago, in the county of Cook and State of Illinois, have invented a new, original, and ornamental Design for a Combined Calendar and Scratch Pad Holder, of which the following is a specification, reference being had to the accompanying drawing, forming a part thereof.

Fig. 1 is a view in perspective of a combined calendar and scratch pad holder showing my new design;

Fig. 2 is a rear perspective view of the same.

I claim:

The ornamental design for a combined calendar and scratch pad holder, substantially as shown.

JAMES H. HORSLEY.
